METHOD OF MANUFACTURING HEAT EXCHANGERS

John Karmazin, Huntington, Ind., assignor to
Karmazin Engineering Company, a corporation
of Michigan

Application December 4, 1935, Serial No. 52,818

4 Claims. (CL. 113—118)

This invention relates to heat exchangers which may be used on refrigerating apparatus or the like.

It is an object of this invention to provide a novel heat exchanger and a novel method of manufacture of such a heat exchanger.

Further objects and advantages of the present invention will be apparent from the following description, reference being had to the accompanying drawings, wherein a preferred form of the present invention is clearly shown.

In the drawings:

Fig. 1 is a view, partly diagrammatic and partly in cross-section, of a refrigerating apparatus including a preferred form of my novel heat exchanger;

Fig. 2 is a view taken transversely to Fig. 1;

Fig. 3 is an enlarged view somewhat similar to Fig. 2, but showing the exchanger in the process of manufacture;

Fig. 4 is a view taken along the line 4—4 of Fig. 3;

Fig. 5 is a view somewhat similar to Fig. 4, showing a slightly modified form of manufacture;

Fig. 6 is a perspective view of a blank of material from which tubes may be made;

Fig. 7 shows an early step in the manufacture of tubing;

Fig. 8 shows an advanced step in the manufacture of tubing;

Fig. 9 shows a portion of a fin before the tube has been applied;

Fig. 10 shows the fin with the tube applied thereto;

Fig. 11 shows another step in the manufacture of the tube;

Fig. 12 is a cross-sectional view of the material taken along the line 12—12 of Fig. 11;

Fig. 13 is a cross-sectional view taken along the line 13—13 of Fig. 11, but showing only the material;

Fig. 14 is a perspective view, somewhat similar to Fig. 10, but showing a modified form of the invention; and

Fig. 15 shows a modified form of tube for the heat exchanger.

This invention is directed to the manufacture of heat exchangers such as condensers, evaporators, radiators and the like. Thus, as indicated in Fig. 1, the heat exchanger may be a condenser, although it is to be understood that any other type of heat exchanger may embody features of my invention.

In Fig. 1, a refrigerating system is indicated somewhat diagrammatically. It includes a com-

pressor 10, which discharges compressed refrigerant through line 11 to the condenser 12. The condensed refrigerant flows through the line 13 to the evaporator 14 placed in the cabinet or other space to be cooled 15. The evaporated refrigerant returns through the line 16 to the compressor 10. The compressor 10 may be driven by an electric motor 17, and the electric motor may be controlled in accordance with refrigeration conditions. Thus the temperature in the cabinet 10 acts upon a thermostatic bulb 18, which actuates a snap switch 19 through the medium of expandible bellows 20, the switch 19 starting the motor and compressor when the temperature in the cabinet reaches a predetermined high limit 15 and stopping them when the temperature reaches a predetermined low limit.

The particular condenser shown in Fig. 1 is adapted to be supported with the brackets 21 and 22 uppermost, these brackets together with the brackets 23 and 24 being secured to any suitable support. The arrangement is such that air may be induced by convection or by forced draft over the fins 25 which are in contact with the tubes 26. The battery of tubes 26 is connected to a header 27 at one end and to a liquid receiver 28 at the other end, the liquid receiver being provided with a header 29. The header 27 includes a semi-circular metal sheet 30 and a substantially flat sheet 31 provided with curled edges 32 around the edges of the sheet 30. The sheet 31 has flanged openings 33 struck therefrom and adapted to receive the tubes 26. The receiver 28 is made of a section of cylindrical tubing, and is provided with flanged end pieces 34 and 35 which are snugly fitted into the tube for welding as hereinafter described. The header 29 is made of a dome-shaped piece of metal having flanges 36 which are adapted to be secured to the cylinder 28 by welding, as hereinafter described. A tube 37 is connected at the bottom of header 29 and extends to the top 38. Gaseous refrigerant enters from the pipe 11 through the nipple 40 in the upper part of header 27 and the gaseous refrigerant flows into the tubes 26 where the refrigerant is condensed. The condensed refrigerant flows to the lower part of the condenser either through the header 29 or through the header 27, the liquid finally rising above the lower end 37a of the tube 37. The head pressure causes the liquid to enter the tube 37 and be discharged over the edge 38 into the receiver 28 from whence the liquid refrigerant flows out the nipple 41 and through the pipe 13 to the evaporator. The presence of the tube 37 prevents liquid refrigerant contained in

the receiver 28 from returning to the header 29. This condenser may be used in a different position, with the flanges 22 and 24 lowermost, in which case the nipple 41 may be placed at the point 41a and the tube 37 may be omitted.

5 The tubes 26 and the fins 25 are secured to each other and to their respective headers as more clearly indicated in Figs. 3 to 14 inclusive. The tubes are formed from flat sheet metal stock 10 in strip form of the character shown in Fig. 6. This stock is initially formed with flanges along the edges by suitable rollers into the shape shown in Fig. 7 or 12. Thereafter it is further bent into the shape shown in Fig. 8 or 14. The tubes may 15 have the edges 50 and 51 relatively flat and abutting each other as shown in Fig. 8, or one of the edges 50a may be provided with a slightly curled flange 52 which fits over the flange 51 as indicated in Fig. 14. In either form, the tube may 20 be bent by a die of the character shown in Fig. 11. After the stock has been given an initial shape either as shown in Fig. 7 or 12, it is drawn through the die 53, which is tapering in section. Another die 54 is placed within the die 53 and 25 the tubing is drawn through the die thus receiving the form either shown in Fig. 8 or Fig. 14. It may be cut into lengths suitable for the particular heat exchanger being manufactured.

After the tube has been cut to the proper length, 30 the fins 25 are fitted over the tubes with the flanges 55 fitting tightly over the tubes. Wires 56 of bonding material are placed within the tubes and thereafter the assembly is run into a welding oven having a reducing atmosphere. During the 35 welding operation, the bonding material melts and forces its way between the flanges 50 and 51 or 50a and 51 and bonds the flanges 55 to the tubes 25. When the material is sheet steel, the wires 56 may be of copper or copper alloy, and 40 the capillary action is such that the copper will rise in the tubes if the tubes are placed in the position shown in Fig. 4 or will flow downwardly if the tubes are placed in the position shown in Fig. 5.

45 The entire assembly may be welded together in the welding oven. In this case, additional pieces of bonding material may be placed in the headers 27 and 29 and in the receiver 28 so that

the ends of the tubes are welded to the headers and the edges of the headers are welded in fluid-tight relationship and the ends 34 and 35 are hermetically sealed to the tube 28.

A slightly modified form of tube is shown in Fig. 15. In this case the metal sheet is bent into the form there shown which includes a semi-circular portion 60 and touching portions 61 and 62. Fins are adapted to be placed over this tube in a manner similar to that heretofore described and the same may be assembled by providing bonding wire 63 as heretofore described.

While the form of embodiment of the invention as herein disclosed, constitutes a preferred form, it is to be understood that other forms might be adopted, all coming within the scope of the claims which follow.

What is claimed is as follows:

1. The method of constructing a heat exchanger which comprises placing perforated fins 20 over an open seamed tube, placing bonding material inside said tube and heating the assembly to cause the bonding material to flow out between the engaging surfaces of the seam and to bond said fins to said tube.

2. The method of manufacturing finned tubing which includes placing apertured fins over open seamed tubes, placing bonding material within said tubes and heating the assembly to cause the bonding material to flow by capillary action between the engaging surfaces of the seam and between said tubes and fins.

3. The method of forming finned tubing which includes placing fins having apertures corresponding to the shape of open seamed tubing 35 over said tubing, placing bonding material within said tubing and heating the assembly to cause the bonding material to flow out at the seam and between the fins and tubing.

4. The method of forming finned tubing which 40 includes placing fins having apertures corresponding to the shape of open seamed tubing over said tubing, placing bonding material within said tubing and heating the assembly to cause the bonding material to flow out at the seam and between the fins and tubing, the bonding material being in the form of longitudinal strips or wires.

JOHN KARMAZIN.
